UNITED STATES PATENT OFFICE.

WILLIAM EARLE, OF PHILADELPHIA, PENNSYLVANIA.

CHIMNEY CAP AND VENTILATOR.

SPECIFICATION forming part of Letters Patent No. 527,199, dated October 9, 1894.

Application filed October 6, 1893. Serial No. 487,343. (No model.)

To all whom it may concern:

Be it known that I, WILLIAM EARLE, a citizen of the United States, residing in the city and county of Philadelphia, in the State of Pennsylvania, have invented a certain new and useful Improvement in Chimney Caps and Ventilators, of which the following is a specification.

My present invention is an improvement upon the chimney cap and ventilator invented by me and forming the subject-matter of Letters Patent No. 405,698, dated June 25, 1889, and the object of my invention is to simplify, cheapen, and improve upon the construction described in the said Letters Patent.

In the accompanying drawings I show and herein I describe a good form of a convenient embodiment of my invention the particular subject-matter claimed as novel being hereinafter definitely specified.

In the drawings, Figure 1 is a central vertical sectional elevation of my improved chimney cap and ventilator. Fig. 2 is a top plan view of the same, the cap being supposed removed. Fig. 3 is an under plan view of the ventilator wheel. Fig. 4 is a view in perspective of the supporting bar and its spindle. Fig. 5 is a view in perspective of a portion of the body of the structure and of one of the screws and nuts by which the supporting bar is maintained in position. Fig. 6 is a view in perspective of the graphite bushing of the ventilator wheel and the device by which it is supported in position.

In the drawings, A represents a cylindrical body or base through which the device rests upon the chimney top, B the protecting cylinder, being a metal cylinder of greater diameter than the chimney and supported in position about the top of the base A, and C is a protecting cap, being a conical cap of metal of about the diameter of the chimney and supported in position above the protecting cylinder.

d are angle irons, the lower extremities of which are secured to the base A, the intermediate portions of which extend radially outward so as to be adapted to be secured to the protecting cylinder B for the support of the latter, and the upper extremities of which are turned inward so as to be adapted to be

secured to the cap C for the support of the latter.

D is a corrugated flange circumscribing the base A and secured to it in any usual manner. 55

The parts so far described are of substantially the construction disclosed in my said former patent, to which reference is to be made for further description of said parts.

My present improvements relate to the devices which support the ventilator wheel and to the construction of said wheel.

E is the supporting bar, the same consisting of a bar of any preferred construction, of length equal to the internal diameter of the base, the extremities of which bar are provided with recesses e and overhanging flanges e'.

e² are screws extending inwardly through holes in diametrically opposite sides of the base, and equipped at their inner extremities with nuts e³.

In the assembling of the parts, the screws e² being supposed in position, the supporting bar is placed within the base and so disposed that its recesses e embrace the respective screws e² and, when in this position, its flanges e' rest upon the upper edge of the base. Upon the tightening up of the nuts e³ the said bar will be firmly secured in position. The central portion of the bar is provided with a lug e⁴, embodying a vertical aperture, through which the screw-threaded lower end of a vertical spindle F extends, said spindle being secured in any desired position of vertical adjustment by the manipulation of nuts f' mounted upon it and disposed respectively above and below said lug. 85

The ventilator wheel is composed of a central many-armed integral hub casting and of sheet-metal blades secured to the arms of said casting. 90

G is the hub casting referred to, the same consisting of a cylindrical body and of a series of arms radially projecting from its lower portion. 95

The radial arms referred to are each slightly inclined from one edge to the other.

g are the series of sheet metal blades, which, with the casting, complete the wheel, the same being mounted upon said arms and secured thereto by screws and nuts g^x. 100

The center of the hub casting is hollow, and contains a bushing g' of graphite or other material adapted to form a bearing which will not require lubrication. I prefer to mount 5 the bushing within said hub casting in the manner shown in Figs. 1, 3 and 6, in which the cylindriform block of graphite which forms the bushing is inclosed in a tube g^2 of sheet metal of length slightly in excess of its own, 10 the extremities of which tube above and below the graphite are cut to form teeth, a number of said teeth being turned inward upon the extremities of the block of graphite to secure the latter in position within the tube, 15 while the remainder of said teeth are bent outward to embrace the ends of the hub casting to secure the tube in position. The block of graphite embodies a recess adapted to receive the spindle F upon which the ventilator 20 wheel is to be seated and with respect to which it is to rotate.

The advantages of my improved structure will be readily understood.

In ventilators of this type the connection 25 between the ventilator wheel and the base with respect to which said wheel rotates has heretofore been made, as shown in my former patent, by securing a spindle rigidly to the ventilator wheel and providing the supporting bar with a hub containing the graphite bushing. In such construction, however, the body of the ventilator wheel (and therefore its center of gravity) has been above its bearing in the stationary hub in the supporting bar, and said hub and the graphite bearing 30 within the hub, have been necessarily of great length in order to secure the ventilator wheel against its tendency to drop to one side or the other as it naturally tended to do by 35 reason of its center of gravity being above its base.

In my improved construction in which the spindle is on the contrary secured to the supporting bar, while the hub and bushing form 40 part of the ventilator wheel, the center of gravity of the ventilator wheel is at the base of the wheel and below the point of said spindle on which the weight of the wheel rests, and therefore a short bearing, being in fact 45 one which is about half the length of that heretofore necessary, is sufficient for the purpose. This reduction in the amount of graphite employed constitutes a great improvement from the standpoint of economy of material, 50 as the graphite is a very expensive substance. The arms which project from the hub casting 55 constitute the bases to which the sheet metal blades of the wheel are secured and the provision of said arms, as integral portions of a 60 single casting, expedites by reason of the ease with which the blades can be secured to said arms, the manufacture of the wheels to such an extent that a workman can turn out nearly

twice as many wheels in a given time than heretofore. The construction heretofore resorted to in this connection has been to manually secure to the central portion of the wheel 65 a series of independent arms and to attach the blades to the arms as an independent operation. In my improved construction however, the arms which are with the hub made as a single integral casting, and are all of one pattern, insure that the blades subsequently applied shall be properly disposed and equidistant, serve to reinforce the strength of 70 said blades, and, by their lateral inclination as shown, secure to the blades when the latter are attached, the proper spiral set necessary to their successful operation. The form and application of the supporting bar are such 75 that said bar may be readily detached and applied. This is a feature of especial value in the transportation of devices of this type from the manufacturer to the user, the devices being ordinarily cumbrous and very 80 liable to damage in shipment. As will be understood, however, my improved device can be packed into very small compass, as, by removing the supporting bar and ventilator wheel, the cap may be placed, apex down 85 within the ventilator wheel chamber, its upwardly turned concave face serving to receive the ventilator wheel, which may be placed therein in inverted position. As thus arranged the device can be packed for transportation in a comparatively small box and the parts will be little liable to damage.

Having thus described my invention, I claim—

1. In a chimney ventilator, in combination, 100 a base, a supporting bar, an upwardly projecting spindle adjustably secured to said bar, and a ventilator wheel mounted on said spindle, substantially as set forth.

2. In a chimney ventilator, in combination, 105 a base, a supporting bar removably attached thereto, an upwardly projecting spindle secured to said bar, and a ventilator wheel consisting of a hub having integral outwardly extending arms or bars which serve as the 110 supports for blades attached thereto, said hub embodying a recess by which it is seated upon said spindle, substantially as set forth.

3. In a chimney ventilator, in combination 115 with the base, projections mounted in said base, a supporting bar having recesses adapted to receive said projections and having flanges adapted to rest upon an edge of the base, substantially as set forth.

In testimony that I claim the foregoing as 120 my invention I have hereunto signed my name this 20th day of September, A. D. 1893.

WILLIAM EARLE.

In presence of—
F. NORMAN DIXON,
JAMES LOUGHREAN.
